(57) **CLAIM**

The ornamental design for an ossicular prosthesis, as shown and described.

DESCRIPTION

FIG. 1 is a top perspective view of the ossicular prosthesis. FIG. 2 is a front side view of the ossicular prosthesis. FIG. 3 is a rear side view of the ossicular prosthesis. FIG. 4 is a left side view of the ossicular prosthesis. FIG. 5 is a right side view of the ossicular prosthesis. FIG. 6 is top view of the ossicular prosthesis; and, FIG. 7 is a bottom view of the ossicular prosthesis. The broken lines illustrate portions of the ossicular prosthesis that form no part of the claimed design.
